UNITED STATES PATENT OFFICE.

ERNEST V. ACHESON, OF SALT LAKE CITY, UTAH.

UMBILICAL FORCEPS AND METAL SEALING-BAND.

SPECIFICATION forming part of Letters Patent No. 789,401, dated May 9, 1905.

Application filed July 15, 1904. Serial No. 216,656.

To all whom it may concern:

Be it known that I, ERNEST V. ACHESON, a citizen of the United States of America, and a resident of Salt Lake City, Salt Lake county, Utah, have invented certain new and useful Improvements in Umbilical Forceps and Metal Sealing-Bands, of which the following is a specification.

My invention contemplates an improved pair of umbilical forceps of that particular character in which the cutting of the umbilical cord and sealing the same by metallic process by the application of metal sealing-bands to the ends of the cord are accomplished in one manipulation of the instrument.

In the accompanying drawings, Figure 1 is an enlarged side elevation of my improved instrument with the jaws closed and showing the handles broken away for convenience of illustration; Fig. 2, a vertical section on line 2 2 in Fig. 1; Fig. 3, a plan of the instrument shown in Fig. 1; Fig. 4, a vertical section on line 4 4 in Fig. 1; Fig. 5, a detail section on line 5 5 in Fig. 3; Fig. 6, a front or end view of one side of the instrument shown in Fig. 1; Fig. 7, a view similar to Fig. 1, but showing the jaws separated and the metal sealing-bands in position to be applied to the cord; Fig. 8, a view similar to Fig. 7, but showing the position of the jaws and parts after the severing of the cord and the application of the clamping-bands; Fig. 9, a full-size view of one of the upper clamping-jaws; Fig. 10, a full-size view of one of the cam-pin and needle carrying plates; Fig. 11, a full-size view of one of the lower clamping-jaws; Fig. 12, a section on line 12 12 in Fig. 10, and Fig. 13 a full-size perspective of one of the metal sealing-bands.

As thus illustrated, my improved pair of umbilical forceps comprises a pair of handles A and B, pivotally connected by a pivot-pin C and provided with cutting-blades a and b. The said blades are provided with openings d' and b', and in these openings the cylindrical cross-heads D and E are inserted, said cross-heads being formed with reduced end portions d' and e' and e'. As shown, the pivot-pin is formed with reduced end portions c and c' and

also with an annular groove c². In this way the handles are pivotally connected by the middle portion of the pin C, and the cross-heads D and E are carried, respectively, by the blades b and a. The sealing-clamps F and G are mounted at opposite sides of the cutting-blades and are operated by the latter when the handles are opened and closed, the jaws of said clamps being carried on the reduced end portions of the cross-heads and pivotally connected by the reduced end portions of the pivot-pin. For example, the clamp F comprises the upper and lower jaws f and f', having openings f² and f³ for the pivot-pin and having also cam-slots f⁴ and f⁵. It will also be seen that the jaw f has a notched opening f⁶ and a pair of prongs f⁷, while the jaw f' is provided with a notched opening f⁸ and three prongs f⁹. Also, as illustrated, the jaw f is formed with slightly-separated disk-like portions f¹⁰, and the jaw f' is formed with similar disk-like portions f¹¹, the portions f¹¹ fitting and working between the portions f¹⁰. Each jaw can be made in one piece; but it is constructed from five superimposed plates which are fastened together by rivets, as shown. The plate f¹², provided with the needle f¹³ and the cam-pin f¹⁴ and having the slot f¹⁵, fits and works between the portions f¹⁰. Keys d² and e², provided with notches, are secured in the end portions d' and e' and adapted to engage the notches of the openings f⁶ and f⁸. Split or notched locking-rings d³ and e³ encircle the portions d' and e' and engage the notches in the keys d² and e². With this provision it is obvious that the jaws cannot be removed from the cross-heads until the rings d³ and e³ are rotated sufficiently to bring their notches into register with the said keys. The said rings are mounted between the plates of which the jaws are composed and are provided with roughened edges to facilitate their rotation. A spring-key H, having a hook-shaped portion h, adapted to engage the groove c² in the pivot-pin, and provided with an opening in its other end adapted to engage the small pin or projection h' on the handle B, serves as the means for holding the blades together. With this arrangement the handle A is secured

to the pivot-pin C, while the handle B is loosely mounted thereon. By disengaging the flexible key from the pin h' its hook-shaped end can be withdrawn from the groove c^2 , so as to 5 leave the handles free to separate. It will be understood that the clamp G is in all respects the same as the clamp F. When the instrument is closed, as shown in Fig. 1, the prongs of the upper jaws interlock with the prongs 10 of the lower jaws, as shown in Fig. 6. At such times the pivot-pin is at the inner end of the slots in the plate f^{12} and the corresponding plate of the clamp G. Also when the jaws are closed the needles on these plates project between the jaws and the cam-pins are at 15 the inner ends of the cam-slots in the interlocking pivotally-connected portions of the jaws.

In use the metal sealing-bands I, each in the 20 nature of a split ring or band having a small hole i adapted to receive one of the needles, are first placed in position, as shown in Fig. 7. The handles are then brought together, so as to cause the edges of the cutting-blades to pass 25 each other and so as to compress the sealing-bands near the ends of the severed cord. This closing of the instrument causes the cam-slots in the disks to act on the cam-pins in such manner as to keep the needles inserted through 30 the openings in the bands. Upon opening the instrument, however, the extreme separation of the handles causes the said cam-slots to act on the cam-pins in such manner as to shift the two plates bearing the needles to the position 35 shown in Fig. 8, thereby withdrawing the needles from the bands. Thus the needles when the cord is cut are allowed to remain in position to keep the ends of the cord from slipping away until after the sealing-bands are properly applied. These sealing-bands are 40 preferably flat in character and of any suitable metal—for example, aluminium.

With the provision of the cross-head having keys and locking-rings it is obvious that 45 the jaws can be easily and quickly removed, thus facilitating cleaning and sterilizing and the taking apart and assembling of the various portions of the instrument; but notwithstanding the readiness with which the instrument 50 can be taken apart and put together it will be seen that the instrument is strong and rigid and that the construction is of such character as to prevent any yielding or slight displacement of the parts during the delicate operation of severing and sealing the cord. Furthermore, the sealing-bands can be clamped 55 down flat upon the cord, thus effectively sealing the ends of the latter.

What I claim as my invention is—

- 60 1. An umbilical forceps comprising blades having cross-heads, a pivot-pin connecting the blades, and a pair of sealing-clamps removably mounted on said cross-heads and pivot-pin at opposite sides of the blades.
- 65 2. An umbilical forceps comprising blades

having cylindric cross-heads, clamping-jaws mounted on said cross-heads, and notched locking-rings rotatably mounted on said cross-heads to lock the jaws in place.

3. An umbilical forceps comprising clamping-jaws, cutting means, and needles operated by the opening and closing movements of the jaws and adapted to hold a couple of metal sealing-bands in position between the jaws. 70

4. An umbilical forceps comprising clamping-jaws, cutting means, and a pair of needles alternately withdrawn from and presented between the jaws by the opening and closing movements of the latter. 75

5. An umbilical forceps comprising cutting means, and clamping-jaws, said jaws having flat opposing faces, whereby a pair of metal sealing-bands may be clamped down flat upon the cord and near the ends of the severed cord. 80

6. An umbilical forceps comprising cutting means, clamping-jaws having flat opposing faces adapted to clamp a pair of metal sealing-bands down flat upon the cord and near the ends of the severed cord, and needles adapted 90 to extend through the bands and engage the cord during the cutting operation, said needles being alternately withdrawn from and presented between the jaws by the opening and closing movements of the jaws. 95

7. An umbilical forceps comprising pivotally-connected clamp-jaws having flat opposing faces adapted to clamp a pair of metal sealing-bands down flat upon the cord, said forceps being provided with cutting means, 100 and also with means for holding said bands in place between the jaws.

8. An umbilical forceps comprising a pair of cutting-blades, a pivot-pin connecting said blades, said pin having an annular groove, 105 and a key-spring having one end engaging said groove and the other end engaging a portion rigid with one of said blades.

9. An umbilical forceps comprising clamping-jaws and cutting means, said jaws being pivotally connected at one end and provided with interlocking prongs at the other end and having also flat clamping-faces between their ends. 110

10. An umbilical forceps comprising clamping-jaws having cam-grooves, and needle-plates provided with cam-pins adapted to engage said grooves, whereby the needles are alternately withdrawn from and presented between the jaws by the opening and closing 120 movements of the instrument. 115

11. Means for effecting a sealing by metallic process of the ends of the severed umbilical cord, comprising a pair of split bands, and a pair of forceps provided with cutting means 125 and flat-faced clamping-jaws adapted to clamp the bands down flat upon the cord near the ends.

12. Means for effecting a sealing of the severed umbilical cord, comprising a pair of split 130

metal bands each provided with an opening opposite its gap.

13. An umbilical forceps comprising clamping-jaws connected by cross-heads having 5 notched keys and rotatable notched locking-rings for removably holding the jaws in place on the cross-heads.

Signed by me at Salt Lake City, Salt Lake county, Utah, this 29th day of March, 1904.

ERNEST V. ACHESON.
